(No Model.)

G. A. BUSH.

FOUNTAIN.

No. 286,261.

Patented Oct. 9, 1883.

Attest;

Walter Fowler
R. K. Evans

Inventor;

Grant A. Bush
by A. H. Evans the
Atty.

UNITED STATES PATENT OFFICE.

GRANT A. BUSH, OF CLEAR LAKE, IOWA.

FOUNTAIN.

SPECIFICATION forming part of Letters Patent No. 286,261, dated October 9, 1883.

Application filed April 19, 1883. (No model.)

To all whom it may concern:

Be it known that I, GRANT A. BUSH, of Clear Lake, in the county of Cerro Gordo and State of Iowa, have invented a new and useful Improvement in Fountains, of which the following is a clear, full, and exact description, reference being had to the accompanying drawings, making a part of this specification, in which—

10 Figure 1 represents the side elevation of a fountain with my improvements attached. Fig. 2 is a vertical section of the same, and Fig. 3 is an enlarged vertical section of the air-chamber.

15 My invention relates to ornamental fountains to be used either in a house or out of doors; and it consists in the combination of devices hereinafter explained and claimed.

20 To enable others skilled in the art to make and use my invention, I will proceed to describe the exact manner in which I have carried it out.

25 In the drawings, A represents the basin of the fountain, in and above the center of which is secured an air-chamber, B, of any desired ornamental form or figure. From the top of this figure rises the tube C, through which the water issues to form the spray. This tube descends through the air-chamber to a point near its 30 bottom. From the bottom of the basin A passes a tube, D, down to a point below the pump E and connected therewith, so as to supply the pump with water from the basin. From the pump a tube, F, passes up to the 35 air-chamber B, through which the water is drawn from the pipe E, and is forced into the

air-chamber, whence it escapes in a spray through the tube C. The pressure of the air in the chamber B causes a regular flow of the water through the pipe E, and avoids the pulsation which would otherwise be caused by the action of the pump.

The pump is operated by the well-known means of a weight and clock-gearing. If the fountain be designed for outdoor use, a hole 45 eight or ten feet deep should be made to receive the weight, and the fountain will play for about one hour for every foot of drop the weight has.

The basin A is placed at any desired height, 50 and the mechanism below is inclosed in the cabinet G, made of any desired pattern.

I am aware that a fountain having a hollow pedestal containing clock mechanism for operating a pump-piston working in a cylinder 55 having a bulb connected thereto, and also an air-chamber to steady the flow of water, are old, and such I do not wish to be understood as claiming, broadly, as of my invention.

Having thus explained my invention, what I 60 claim as new, and desire to secure by Letters Patent, is—

In an ornamental fountain, the basin A, air-chamber B, placed above the basin, and tube C, in combination with the tubes D and 65 F, cabinet G, and the pump E, with suitable mechanism for operating the same, substantially as and for the purpose set forth.

GRANT A. BUSH.
